UNITED STATES PATENT OFFICE.

CHARLES E. PITTINGER, OF FALLS CITY, NEBRASKA, ASSIGNOR OF ONE-HALF TO
BLAINE GOODGER, OF FALLS CITY, NEBRASKA.

GREASE RETAINER.

Application filed July 18, 1920. Serial No. 395,977.

To all whom it may concern:

Be it known that I, CHARLES E. PITTINGER, citizen of the United States, residing at Falls City, in the county of Richardson 5 and State of Nebraska, have invented certain new and useful Improvements in Grease Retainers, of which the following is a specification.

This invention relates to improvements 10 in grease retainers especially adapted for use on the side rods of locomotives though obviously not restricted to such use.

An important object of this invention is to provide novel means whereby the grease 15 plug and consequently the grease in the bearing end of the side rod of a locomotive may be prevented from loss due to the reciprocation of the rod.

A further object of the invention is to 20 provide a device of the class described which may be readily and conveniently applied to the side rods of a locomotive without necessitating any changes in the construction of the side rods or without interfering with the operation of the same and 25 which may also be removed without inconvenience when it is desired to repair the side rod.

A further object of the invention is to 30 provide a device of the class described which is of highly simplified construction, durable in use, and cheap to manufacture.

Other objects and advantages of the invention will be apparent during the course 35 of the following description.

In the accompanying drawings forming a part of this application and in which like numerals are employed to designate like parts throughout the same,

40 Figure 1 is a perspective of the device applied, the cover thereof being shown open,

Figure 2 is a side elevation of the device applied,

45 Figure 3 is a central vertical sectional view through the device applied,

Figure 4 is a horizontal section taken on the line 4—4 of Figure 3,

Figure 5 is a fragmentary perspective of the device, the view illustrating a slightly 50 modified form of base plate.

In the drawings wherein for the purpose of illustration is shown a preferred embodiment of the invention, the numeral 10 generally designates one of the side rods of a 55 locomotive having a bearing 12 which is

supplied with grease through a passage or channel 14 in the head 15 of the bearing.

As illustrated in Figure 3 of the drawings, the head 15 is provided with an interiorly threaded grease pocket or reservoir 60 16 with which the grease passage 14 communicates so that the grease contained within the pocket 16 may be supplied to the bearing 12. The grease pocket or reservoir receives a threaded bushing 17 having a 65 polygonal head 18 adapted to be engaged by a wrench so that the bushing may be applied or removed by threading the same into the pocket. An annular shoulder 20 formed on the bushing serves as a means for limiting the inward movement of the same. The grease within the pocket 16 may be forced through the channel 14 by screwing up on a grease retaining plug 22 having a polygonal head 24 adapted to be engaged by a 75 suitable wrench.

Due to the rapid movement or reciprocation of the side rod 10 during the travel of the locomotive, the grease plug 22 frequently becomes lost and consequently allows 80 the grease within the bushing to also become lost. This loss of the grease or lubricant within the bushing allows the bearing to run hot with the result that the bearing is soon rendered useless and can be replaced 85 only at the expenditure of much time and new material.

To overcome the above difficulty, I have devised a protector 26 which consists of a base plate 28 having a centrally arranged 90 opening to receive the attaching portion of the bushing 17 so that when the bushing is screwed to the limit of its movement into the pocket 16, the base plate 28 will be held firmly in position. The base plate 28 is 95 only slightly larger than the bushing and therefore occupies but a minimum amount of space and does not in any way interfere with the operation of the rod or the supplying of grease to the bearing of the same. 100 A hollow casing 30 is adapted to be arranged over the grease plug 22 so as to prevent the same from becoming accidentally disconnected from the bushing 17 and said casing is provided with a reinforcing plate 105 32 formed with a lateral extension 34 which is hingedly connected to the plate 28 by means of a hinge pin 36 extending through aligned hinge lugs 38 in the plate and the extension 34. When it is desired to en- 110

tirely detach the casing 30 from the plate 28, it is merely necessary to remove the pin 36 extending through the hinge lugs 38 and subsequently remove the casing. The rearwardly extending portion 34 of the reinforcing plate 32 is braced by a strap 39 extending from the plate to the extension 34 and secured to the same by fastening devices in the form of rivets or the like.

10 The casing 30, which is of hexagonal formation snugly and slidably receives a plate 42 pressed into engagement with the grease plug 22 by a coil spring 43. The end portions of the coil spring 43 are flared or enlarged and are connected to the plate and to the inner end of the casing by means of rivets 43. In flaring or enlarging the end portions of the coil spring the same are caused to bear flatly against the casing and 15 the pressure plate 42 and thereby prevent the spring from collapsing.

As illustrated in Figure 3, the pressure plate 42 bears flatly against the upper end of the plug 22 and thereby prevents the plug 20 from being lost during the operation of the locomotive.

The means employed for detachably positioning the casing 30 over the grease plug 22 comprises a substantially U-shaped yoke 46 having arms flared outwardly at their end portions and secured to the sides of the casing by means of rivets 47 or the like. A guiding bracket or plate 48 is arranged between the sides of the yoke and slidably receives a plunger 50 which is adapted to be extended through an apertured ear 52 extended up from the base plate and disposed between the sides of the yoke 46. As illustrated particularly in Figures 3 and 4, a coil spring 54 is confined between the bright portion of the U-shaped yoke and a collar 56 arranged on the plunger and said coil spring serves as a means for urging the plunger forwardly through the apertured ear 52.

The outer end portion of the plunger 50 is formed with a looped handle 58 by means of which the plunger may be released from its connection with the apertured ear 52.

50 In applying the improved protector the base plate 28 is arranged upon the head 15 so that the bushing 17 when applied will secure the same firmly in position. After the bushing and the grease plug 22 have 55 been secured to the plate as illustrated in Figure 3, the casing may be swung over the

plug so that the pressure plate 42 will be flatly engaged with the plug.

Of course, the plunger 50 is retracted preparatory to swinging the casing 30 over the plug and is subsequently released so that the plunger may pass through the apertured ear 52.

It will be noted that the spring presses the plate 42 firmly into engagement with the plug so that the plug is absolutely prevented from loss. A further function of the coil spring 43 is to prevent the casing and associated parts from rattling since the spring exerts a constant outward pressure on the casing and thereby firmly engages the forward portion of the plunger with the apertured ear 52.

In the form of the invention illustrated in Figure 5, the plate 28 is formed with elongated hinge barrels 60 between which the cylindrical hinge barrel of the extension 34 is adapted to be arranged so that a hinge pin 62 may be extended through the aligned barrels. The plate is, in this invention, thus connected to the extension so as to be capable of a sliding movement with relation to the same. Therefore, should the grease plug or retainer 24 be unusually large, the casing 30 may be moved laterally when swung to an open position.

When it is desired to repair the rod, it is merely necessary to remove the casing by detaching the hinge pin 36. If desired, the plate 28 may be connected to the head 12 by means of screw bolts or other suitable means.

It is to be understood that the form of the invention herewith shown and described is to be taken as a preferred embodiment of the same and that such minor changes may be made as will remain within the spirit of the invention and the scope of what is claimed.

Having thus described the invention, what is claimed as new is:

A device of the character described including a base plate provided with an upstanding apertured ear, a casing hingedly connected to the base plate, locking means within the casing to coact with a plug for holding the plug against displacement, a yoke extending laterally from the casing, and a spring pressed plunger slidable upon the yoke to coact with said ear for securing the casing closed.

In testimony whereof I affix my signature.
CHARLES E. RITTENGER. [L.S.]
